UNITED STATES PATENT OFFICE.

HENRY WILSON AND HENRY L. CRUMBLY, OF RICHLAND, GEORGIA.

SUGAR-CANE CRUSHER.

SPECIFICATION forming part of Letters Patent No. 757,988, dated April 19, 1904.

Application filed July 3, 1903. Serial No. 164,179. (No model.)

To all whom it may concern:

Be it known that we, HENRY WILSON and HENRY L. CRUMBLY, citizens of the United States, residing at Richland, in the county of 5 Stewart and State of Georgia, have invented certain new and useful Improvements in Sugar-Cane Crushers; and we do hereby declare the following to be a full, clear, and exact description of the invention, such as will 10 enable others skilled in the art to which it app pertains to make and use the same.

Our invention relates to improvements in mills for grinding sugar-cane, sorghum, or the like, and it is more especially intended for 15 small mills, which may be put up without the expensive foundations required in the larger plants and which may be operated either by hand-power, by machinery, or by horse-power.

Our invention will be understood by reference to the accompanying drawings, in which the same parts are indicated by the same letters throughout both views.

Figure 1 is an end view, parts being broken 25 away; and Fig. 2 is a section on the line 2 2 of Fig. 1 and looking in the direction of the arrows.

The shafts of the four rollers C, C', C², and C³ are journaled in journal-boxes in the housing, which is comprised of two plates A and A', provided with lugs a and a' and connected together by the bolts B and B', passing through said lugs. The opposite lugs a are separated by washers b, while the lugs a' are separated 30 by a stiff coil-spring B², as seen in Fig. 2. To ease the strain on the back rollers C² and C³, cup-springs B³ may be mounted beneath the nut b' on the bolt B, as seen to the right of Fig. 2. Also the mill may be adjusted by 40 easing up or screwing down on the nut on the bolt B'.

The two plates A and A' are preferably provided with interpenetrating arms a², a³, a⁴, and a⁵ to prevent the cane or bagasse from 45 passing out laterally and fouling the gearing.

Across the front of the mill the guard-plate D is mounted, which is secured on the tie-bolts E by means of the slotted lugs d. This guard-plate has a V-shaped piece D' project- 50 ing inward from its sides, which piece pro-

jects into the space between the rollers C and C', as shown in Fig. 2, while the top and bottom of the plate is cut away and bent in, as at D², and sharpened to form scrapers and also guards for the rollers. Thus it will be 55 seen that the two side pieces D' and the top and bottom pieces D² of the plate D form a sort of funnel into which the cane or sorghum is fed.

Scrapers D³ are provided at the back of the 60 mill, which clean the rollers of the bagasse and cause the same to be delivered behind the mill. These scrapers are mounted on the tie-bolts E', spanning the back of the mill and are generally similar to the tie-bolts E. The 65 scrapers D³ may be adjusted by means of clamp-bolts or screws e.

R represents a perforated turn-plate, which is mounted between the lower rollers and prevents the bagasse from dropping down 70 between the same. The rollers turn in the direction indicated by the arrows.

F represents a combined bed-plate and trough at the bottom of the mill, into which the expressed juice falls and from which it is 75 delivered through the spout f. This combined bed-plate and trough is mounted on feet F' above the foundation on which the mill rests, and the housing-plates A' are secured thereto, as by means of bolts a'. 80

The mill may be driven either by hand-crank K and handle K' or by a belt (not shown) over the pulley I or by horse-power connected to the head L.

Where the mill is to be driven from the pulley I, the head L, with the beveled gear L² fast thereto, is preferably removed from the pivot L' and the handle K is detached from the shaft H. Where it is to be driven by hand-power, the beveled gear L² and head L 90 may be preferably left off. Where it is to be driven by horse-power, the handle alone may be removed. No matter what kind of power be used the shaft H is turned, and the gears H' and H², fast thereon, turn therewith. These 95 gears mesh with the spur-gears M and P, mounted on the shafts M' and P' of the upper rollers C and C², respectively, and thus turn these rollers. Fast on the shaft M' is a second gear M², which meshes with the gear N 100

on the shaft N' of the roller C' , whereby this roller is caused to turn. Fast on the shaft P' is a second gear P^2 , which meshes with the gear Q , fast on the shaft Q' , whereby the back 5 roller C^3 is turned. Thus it will be seen that the rotation of the shaft H in the proper direction causes all of the rollers to revolve and that this rotation may be produced either by the pulley I , by horse-power, or by hand.

10 It will be obvious that other applications of power may be used to rotate the shaft H and that the mill may be made larger or smaller, as desired. The back rollers should be mounted closer together than the front, so as to distribute 15 the compression between the rollers, and, moreover, the back rollers should preferably be larger and with heavier shafts in order to secure better extraction of the juice.

15 It will be obvious that various modifications 20 might be made in the herein-described apparatus which could be used without departing from the spirit of our invention.

Having thus described our invention, what 25 we claim, and desire to secure by Letters Patent of the United States, is—

1. In a mill of the character described, the combination with the combined bed-plate and trough, of the lower housing-plates secured thereto, the upper housing-plates hinged to the 30 lower, rollers journaled in said housing-plates, a shaft journaled across the upper housing-plates, gearing connecting said shaft and the shafts of all of said rollers, and means for turning 35 said shaft, substantially as described.

2. In a mill of the character described, the combination with the combined bed-plate and trough, of the lower housing-plates secured thereto, the upper housing-plates hinged to the lower, rollers journaled in said housing-plates, 40 a guard-plate cut away at its center to form a funnel and scrapers in front of the front rollers, a perforated turn-plate mounted between the lower pair of rollers, a shaft journaled across the upper housing-plates, gearing connecting 45 said shaft and the shafts of all of said rollers, and means for turning said shaft, substantially as described.

3. In a mill of the character described, the combination with the combined bed-plate and trough, of the lower housing-plates secured thereto, the upper housing-plates hinged to the lower, rollers journaled in said housing-plates, a guard-plate cut away at its center to form a funnel and scrapers in front of the front 55 rollers, scrapers in rear of the rear rollers, a perforated turn-plate mounted between the lower pair of rollers, and means for turning said rollers, substantially as described.

4. In a mill of the character described, the combination with the combined bed-plate and trough, of the lower housing-plates secured thereto, the upper housing-plates hinged to the lower, rollers journaled in said housing-plates, a guard-plate cut away at its center to 65 form a funnel and scrapers in front of the front

rollers, scrapers in rear of the rear rollers, a perforated turn-plate mounted between the lower pair of rollers, a shaft journaled across the upper housing-plates, gearing connecting said shaft and the shafts of all of said rollers, 70 and means for turning said shaft, substantially as described.

5. In a mill of the character described, the combination with a suitable support, of the lower housing-plates mounted thereon, the upper housing-plates hinged to the lower, rollers journaled in said housing-plates, a guard-plate cut away at its center to form a funnel and scrapers in front of the front rollers and adjustable scrapers in rear of the rear rollers, 80 a turn-plate mounted between the lower pair of rollers and means for turning said rollers, substantially as described.

6. In a mill of the character described, the combination with a suitable support, of the lower housing-plates mounted thereon, the upper housing-plates hinged to the lower, rollers journaled in said housing-plates, a guard-plate cut away at its center to form a funnel and scrapers in front of the front rollers, 90 scrapers in rear of the rear rollers, a turn-plate mounted between the lower pair of rollers, a shaft journaled across the upper housing-plates, gearing connecting said shaft and the shafts of all of said rollers, and means for 95 turning said shaft, substantially as described.

7. In a mill of the character described, the combination with the combined bed-plate and trough, of the lower housing-plates secured thereto, the upper housing-plates hinged to the lower, tie-bolts connecting the opposite pairs of housing-plates, rollers journaled in said housing-plates, a guard-plate mounted on the front tie-bolts and cut away at its center to form a funnel and scrapers in front of the front 100 rollers, scrapers mounted on the rear tie-bolts in rear of the rear rollers, a perforated turn-plate mounted between the lower pair of rollers, and means for turning said rollers, substantially as described.

8. In a mill of the character described, the combination with the combined bed-plate and trough, of the lower housing-plates secured thereto, the upper housing-plates hinged to the lower, tie-bolts connecting the opposite 115 pairs of housing-plates, rollers journaled in said housing-plates, a guard-plate mounted on the front tie-bolts and cut away at its center to form a funnel and scrapers in front of the front rollers and adjustable scrapers 120 mounted on the rear tie-bolts in rear of the rear rollers, a perforated turn-plate mounted between the lower pair of rollers, a shaft journaled across the upper housing-plates, gearing connecting said shaft and the shafts of all of 125 said rollers, and means for turning said shaft, substantially as described.

9. In a mill of the character described, the combination with the combined bed-plate and trough, of the lower housing-plates secured 130

thereto, the upper housing-plates hinged to the lower, tongues projecting from said housing-plates and forming guards for the gear-wheels, rollers journaled in said housing-
5 plates, and means for turning said rollers, substantially as described.

10. In a mill of the character described, the combination with the combined bed-plate and trough, of the lower housing-plates secured thereto, the upper housing-plates hinged to the lower, tongues projecting from said housing-plates and forming guards for the gear-wheels, rollers journaled in said housing-
15 plates, a shaft journaled across the upper housing-plates, gearing connecting said shaft and the shafts of all of said rollers, and means for turning said shaft, substantially as described.

11. In a mill of the character described, the combination with the combined bed-plate and trough, of the lower housing-plates secured thereto, the upper housing-plates hinged to the lower, tongues projecting from said housing-plates and forming guards for the gear-
25 wheels, rollers journaled in said housing-

plates, a guard-plate cut away and bent in at its center to form a funnel in front of the front rollers, and means for turning said rollers, substantially as described.

12. In a mill of the character described, the combination with a suitable support, of the lower housing-plates mounted thereon, the upper housing-plates hinged to the lower, tongues projecting from said housing-plates and forming guards for the gear-wheels, rollers journaled in said housing-plates, a guard-
30 plate cut away at its center to form a funnel in front of the front rollers, a perforated turn-plate mounted between the lower pair of rollers, a shaft journaled across the upper hous-
35 ing-plates, gearing connecting said shaft and the shafts of all of said rollers, and means for turning said shaft, substantially as described.

In testimony whereof we affix our signatures in presence of two witnesses.
